Asa Barrett of Baltimore Md

Letters Patent (Stat. Apr. 21. 1830) 22

The Schedule referred to in these Letters Patent, and making part of the same containing a description on the words of the said Asa Barrett himself of his "Improvement in splitting Corn Husks from Mattocks".

To all to whom these presents shall come. Be it known that I, Asa Barrett, of the City of Baltimore, and State of Maryland, have invented a new and useful machine for splitting the husks of corn from Mattocks, and other purposes, where splitting is required. The machine consists of a firm and substantial frame, of timber about five and a half feet long, three feet wide, and two and a half feet high, or the dimensions may be varied to suit convenience. Upon this frame is attached by bolting, another frame of smaller dimensions, extending from one end to nearly the middle. A crooked end of this second frame is a roller over which a cloth apron revolves, for the purpose of drawing the husks into the machine. On the inner end of this second frame, is another vertical frame, about half the length of the second, attached to it by bolting, so as to form an angle with the second one, of about four or more degrees, with a like roller at each end, over which another apron revolves. The first roller of each frame coming nearly in contact with the other, and being connected or geared, at one end by two cog wheels moving the apron and compressing the husks so as to pass between the rollers. As near to this second roller as may be practicable are placed two flat iron rollers, of the same size, one immediately under the other connected by two cog wheels, at one end, that move at the same speed as the apron rollers. On each end of the upper journal of the flat iron roller is a lever which is to be pressed so as to admit a motion upward to lift the bulk introduced, and to compress the husks and prevent them being drawn out from between them while undergoing the operation of splitting. Nearly as possible to the rollers, and ex-

actly over each other, are two small iron cylinders, or rollers, about one inch and a fourth in diameter, into which are inserted two or more rows, of steel points or knives, about the circumference of a inch long in a spiral direction, each row passing round one half the circumference of the cylinders or rollers. These steel points or knives are so near together that they will split the husk into as fine fibers as may be required. These points are set one space further to the right or left on one cylinder than they are on the other, to prevent their coming in contact. These cylinders or rollers are also connected at one end, by small cog-wheels which revolve with great speed, and are so placed when geared, that the points will penetrate the husks at the upper and lower side at the same time.

Next, as possible to these splitting cylinders, is a large cylinder, about two feet in diameter, in which are driven eight or more rows of flat points, or knives, in a spiral direction, of about one fourth of the circumference, at the same distance from each other as those in the splitting cylinders, but are set one space further to the right or left, so as to pass those of the splitting cylinders without coming in contact with them.

The steel points or knives of this cylinder revolve with greater speed than those of the splitting cylinders, so as to clear the points of those cylinders from husks, and prevent their being thrown over or wound round them, under the splitting cylinders, and as near as possible to the knives of the large cylinder comes a bar of iron, confined to the frame on each side, on which is secured a thick plate of iron containing two rows of steel points or knives, like those of the main or large cylinders, but are set twice the distance apart from each other of those in that cylinder, and the knives in one row are exactly opposite the center of the space between the knives of the other row, and escape those of the large cylinder. The utility of these knives is to separate the fibers after having been split, should any be connected at either end of the husk. From this bar the main, or large cylinder is enclosed in a light case, except a small space, which is left open at the back end to discharge the husks after having passed through the machine, &c.

one end of the shaft of the large cylinder, is a pulley, around which a belt passes to put the machine in operation. On the same end of the shaft between this first pulley and the cylinder is, another pulley around which a belt passes, and extends around one of very small dimensions, on the shaft of the upper splitting cylinder, giving to those cylinders a motion of revolution, to one of the large cylinders. At the other end of the shaft of this large cylinder is a very small cog-wheel or pinion which plays into a cog-wheel of five or six times its size. To this large wheel is attached a pinion, which gives motion to a cog-wheel of about the size of the former, or large wheel. This last mentioned large wheel, is connected with one of much smaller size, on the end of the shaft of the under fluted roller. This last also, is connected with one of exactly the same size, on the end of the shaft of the upper feeding roller on which the apron revolves giving the feeding and the compressing, or fluted rollers, the same speed, and such speed as is required to feed the machine, and completing the movement of the whole. The bunches are prepared by separating them from the stone and throwing out those of poor quality and all hard substances. They are then laid straight and evenly on the apron.

We claim the structure of the machine as above described, as well as the application for the purposes, and uses mentioned in this Specification.
